Primary Examiner — Antoine D Davis(74) *Attorney, Agent, or Firm* — Coats & Bennett, PLLC(57) **CLAIM**

The ornamental design for a tape measure housing, as shown and described.

DESCRIPTION

FIG. 1 is a perspective view of a tape measure housing according to an embodiment of the invention.

FIG. 2 is a left side view of the tape measure housing of FIG. 1.

FIG. 3 is a front view of the tape measure housing of FIG. 1.

FIG. 4 is a right side view of the tape measure housing of FIG. 1.

FIG. 5 is a back view of the tape measure housing of FIG. 1.

FIG. 6 is a top view of the tape measure housing of FIG. 1; and,

FIG. 7 is a bottom view of the tape measure housing of FIG. 1.

The portions of the tape measure housing shown in broken lines are environmental only and form no part of the claimed design.

1 Claim, 7 Drawing Sheets# US D782,350 S
